(57) **CLAIM**

The ornamental design for a wrench joint as shown and described.

DESCRIPTION

FIG. 1 is a perspective view of a wrench joint showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is another perspective view thereof showing a using condition with a ratchet wrench.

The broken lines depict portions of the wrench joint that form no part of the claimed design. The additional broken lines of FIG. 7 show the wrench joint in an environment of use and form no part of the claimed design.
